HARRY C. GAMMETER, OF CLEVELAND, OHIO, ASSIGNOR TO THE AMERICAN MULTIGRAPH COMPANY, OF CLEVELAND, OHIO, A CORPORATION OF OHIO.

LINOTYPE CASTING MECHANISM.

1,122,723.

Specification of Letters Patent.

Patented Dec. 29, 1914.

Application filed August 8, 1913. Serial No. 783,721.

To all whom it may concern:

Be it known that I, HARRY C. GAMMETER, a citizen of the United States, residing at Cleveland, in the county of Cuyahoga and State of Ohio, have invented a certain new and useful Improvement in Linotype Casting Mechanism, of which the following is a full, clear, and exact description, reference being had to the accompanying drawings.

The object of this invention is to provide simple and effective means for making line slugs of short height and grooved on their opposite sides. Such slugs are very useful in printing machines having railed chases, in marking machines, in address plates, etc. My invention comprises a mold adapted to be mounted on the mold wheel of a standard Mergenthaler or linotype machine and adapted to coöperate with the melting pot and matrices for the casting of a line slug having a base portion and a head portion which is grooved on its opposite sides. After casting, the base portion is broken off, or otherwise severed, leaving the line slug of the form desired.

The characteristics of the invention are hereinafter fully explained and are summarized in the claims.

In the drawings, Figure 1 is a side elevation of a portion of a mold wheel of a Mergenthaler machine equipped with my special mold; Fig. 2 is a radial section through such wheel showing a cross section of the mold; Figs. 3, 4 and 5 are cross sections of the mold on the correspondingly numbered lines on Fig. 1.

As shown in the drawing, 10 represents the mold wheel of a line casting machine. My mold is carried by this wheel and comprises a pair of members 11 for the body of the slug, a pair of members 12 for the head of the slug, and a pair of members 13 for the end of the slug. The members 11 comprise two bars or blocks seating in an opening in the mold wheel and having their inner faces parallel and spaced apart, according to the width of the shank of the slugs. These bars 11 are provided near their ends with ears 15, between which are carried the tongues 16 of the end blocks 13. The end blocks are rigidly clamped in place by screws 17 screwing through the ears. This makes a rigid rectangular frame bounding the body of the slug. This frame

is set into a correspondingly shaped opening in the mold wheel and is secured thereto by screws 20 which pass through side flanges 21 of the block 11.

The members 12 which form the mold for the head portion of the slug have peculiarly formed coöoperating faces, namely, at the inner edge of the face is a bevel 24 joining the outer face of the shank portion of the mold opening and leading inwardly therefrom; then the face has a groove 25; outside of this groove is a rib 26, and, beyond the rib, a rabbet 27 leading to the outer side of the block 12. When the lines of matrices 30 (Fig. 2) are against the blocks 12, a mold space is provided corresponding to the slug A, B there shown. After such slug is cast and removed from the mold, it is only necessary to remove the portion B from the head portion A, by breaking it off, for example, to leave a line slug which is of short height and grooved on its opposite sides; that is to say, a slug corresponding to the portion A in Fig. 2.

To enable the removal of the cast slug A, B, I mount the members 12 pivotally on the members 11. To effect this the members 12 may have ears 32 which extend onto opposite ends of ears 33 formed on the blocks 11, and hinge pintles 34 pivot the ears together. A spring 35 surrounding the pintle 34 and bearing, as shown, against the blocks 12 and against the mold wheel, tends to keep these blocks in the seated position shown. In this position beveled ribs 37 on the blocks 12 seat in correspondingly formed grooves in the blocks 11 and accurately position the blocks 12 to hold them against displacement during casting.

After the casting operation, the mold wheel turns the mold to a position opposite a suitable plunger, and such plunger, acting against the foot of the cast slug, shoves the whole slug outwardly between the movable members 12, these members swinging on their pivot rods to allow the slug to clear them. This clearing action is made easier by slotting the eyes in the ears 12 about the rod 34, as shown at 39 in Fig. 5. Also the grooves 25 may be slightly rounded at one or both inner edges.

In casting, the mold is held as rigid as if it were a solid member, but, at the ejection point, as soon as the ejector begins to shove out the cast slug, the members 12 are freed,

by reason of their beveled ribs 37 swinging free from the corresponding grooves in the members 11, and this lets the members 12 separate slightly (by reason of the slots 39), so that they roll out from the grooves cast in the slug and easily clear it, the body of the slugs being shoved between the swung members into any suitable receptacle.

Having thus described my invention, what I claim is:

1. In a device of the character described, the combination of a mold for the body portion of a slug, and a coacting mold for the head portion thereof comprising two pivotally mounted members.

2. In a device of the character described, the combination of a mold for the body portion of a slug, and a mold for the head portion thereof comprising two members hinged to the body mold.

3. The combination of a mold wheel, a body mold mounted thereon, and a mold for the head of the slug comprising two coacting oppositely facing hinged members.

4. The combination of a mold wheel, a body mold mounted in a recess in the wheel, and a mold for the head of the slug comprising two coacting oppositely facing hinged members.

5. The combination of a mold wheel, a body mold mounted in a recess in the wheel, and a mold for the head of the slug comprising two coacting oppositely facing members pivotally mounted on portions of the body mold.

6. The combination of a pair of coacting members for defining the opposite sides of a body of the slug, said members having outwardly extending ears, and a pair of coacting members for the head portion of the slug hinged to said ears.

7. The combination of a mold for the body portion of the slug and two hinged members forming molds for the opposite sides of the head portion of the slug, and springs tending to seat said hinged members against the body mold.

8. The combination of a mold wheel, a body mold rigidly carried thereby, and a mold for the head of the slug comprising two coacting oppositely facing hinged members, and springs tending to seat said members.

9. The combination of a pair of coacting members for defining the opposite sides of a body of the slug, said members having outwardly extending ears, a pair of coacting members for the head portion of the slug hinged to said ears, and springs tending to seat the last mentioned members against the first mentioned members.

10. The combination, with a body mold, of two hinged members for the opposite sides of the head portion of the slug, said members and body mold being provided

with coacting beveled ribs and recesses to accurately seat the hinged members.

11. The combination, with a body mold, of two hinged members for the opposite sides of the head portion of the slug, said members and body mold being provided with coacting beveled ribs and recesses to accurately seat the hinged members, and springs tending to seat such members.

12. The combination of a pair of side members for the mold of the slug body, a pair of hinged members for the mold of the head, and blocks for the end of the slug coacting with both the side members and the hinged members.

13. The combination of a pair of side members for the mold of the slug body, a pair of hinged members for the mold of the head, and blocks for the end of the slug coacting with both the side members and the hinged members, said end blocks extending between and being secured to the side members of the body mold.

14. The combination of a pair of side bars for the mold of the slug body, a pair of hinged members for the mold of the head, and blocks for the ends of the slug coacting with both the side bars, the said side bars projecting beyond the hinged members, and the end blocks being mounted between the projecting portions of the side bars and extending across the ends of the hinged members.

15. The combination of a mold for the body portion of the slug and two hinged members forming molds for the opposite sides of the head portion of the slug, said hinged members and the body mold being provided with coacting beveled ribs and grooves.

16. The combination, with a body mold, of two hinged members for the opposite sides of the head portion of the mold, said members and body mold being provided with coacting beveled ribs and recesses to accurately seat the hinged members against the body mold, the inner faces of the hinged members flaring to register with the faces of the body mold.

17. The combination, with a body mold, of two hinged members for the opposite sides of the head portion of the mold, said members and body mold being provided with coacting beveled ribs and recesses to accurately seat the hinged members, and means providing loose play at the hinges of the members.

18. The combination of a pair of side members for the mold of the slug body, a pair of hinged members for the mold of the head, and blocks for the end of the slug coacting with both the side members and the hinged members, said end blocks extending between and being secured to the side members of the body mold, and a mold

wheel having a recess receiving the side members and a portion of the end blocks.

19. The combination, with a mold wheel having a recess, of a pair of side bars for the mold of the slug body, said side bars seating in the recess and having portions projecting onto the face of the wheel, a pair of members for the mold of the head, said members being hinged to the projecting portions of the side bars, blocks for the ends of the slug coacting with both the side

bars and the hinged members, and the end blocks being mounted between said side bars and extending across the ends of the hinged members.
